SUBSTATION RINGER HAVING PERMANENT
MAGNET ARMATURE

Sidney Reynell Smith, Liverpool, England, assignor to Automatic Telephone & Electric Company Limited, Liverpool, England, a British company

Application June 7, 1947, Serial No. 753,291
In Great Britain June 21, 1946

5 Claims. (Cl. 177—7)

1

The present invention relates to signalling devices and is more particularly concerned with ringing arrangements or ringers which are particularly applicable for use in telephone and like signalling systems.

The main object of the invention is to provide, in a ringer employing a permanent magnet armature, arrangements whereby the size of the ringer is reduced, its operational efficiency is increased and the adjustments are simplified.

According to one feature of the invention, the bell hammer is rigidly fixed to the permanent magnet armature in such a manner as to eliminate relative movement between the hammer and armature at the moment of impact with the gong.

According to a further feature of the invention, the permanent magnet armature is mounted in such a position with relation to the point of impact of the hammer with the gong that its centre of gravity moves substantially towards the point of impact whereby in conjunction with a rigid connection between the armature and the hammer, the impact has behind it the full momentum of the moving structure.

According to yet another feature of the invention, a non-magnetic plate is pivoted at one end and at the other end is provided with projections which act as hammer heads, the permanent magnet armature being rigidly secured to said plate in a position intermediate to said projections, suitable electromagnetic means being provided which when energised by alternating current cause an arcuate reciprocating motion of the moving structure about the pivots.

These and other features of the invention will be better understood from the following description of one embodiment shown in the accompanying drawings in which—

Fig. 1 shows a partial view of the ringer,

Fig. 2 shows a sectional view along the line A—A of Fig. 1 and

Fig. 3 shows a sectional view along the line B—B of Fig. 1.

A mounting plate 38 is provided for carrying the gongs 32, 33 and the two electromagnets 10, 11. The gongs are secured to pillars 34, 35 by means of screws 36, 37, the screws also serving to secure in position a bridge having downwardly extending flanges 31, shown in Figs. 1 and 3.

The electromagnets 10, 11 are provided with polepieces 12, 14 and 13, 15 respectively, the polepieces being secured to the ferrous metal cores 39 and 40 of the electromagnets by means of screws 16, 18, 17 and 19. The free ends of the

2

polepieces are formed of reduced portions 20, 21, 22 and 23 and the windings of the electromagnets are brought out to tags 24, 25, 26 and 27. The electromagnets are secured to the underside of the mounting plate 38 by securing the polepieces thereto by means of screws 41, the polepieces passing through suitable slots in the mounting plate.

The downwardly extending flanges 31 of the bridge form bearings for a pivoted member 30 which carries a plate or hammer 28 of non-magnetic material to which is secured the permanent magnet 29. As shown in Fig. 1, the hammer 28 is provided at its lower end with oppositely extending projections which form the hammer heads. The permanent magnet is cylindrical in shape and is made of high quality magnet steel while it is magnetised to form N and S poles as shown in Figs. 2 and 3. In the normal condition of the ringer, the permanent magnet assumes a substantially symmetrical position with respect to the two pairs of polepieces, as best shown in Fig. 1. The windings of the electromagnets are so connected that, when the electromagnets are energised by an alternating current, two dissimilar poles are formed at each end of the permanent magnet. For example, referring to Fig. 2, during one half cycle of the alternating current, north and south poles might be formed at polepieces 21 and 23 respectively when south and north poles would be formed at polepieces 20 and 22 respectively. The armature will thus be moved to the left while on the succeeding half cycle of the alternating current, the polarity of the polepieces will be reversed and the armature will be moved to the right.

It will be appreciated that the invention is not limited to the embodiment described above but that alternative constructions are possible. For instance, one electromagnet only may be employed together with a plain ferrous metal return path provided with polepieces the effect of which is to cause the armature to assume a normal position which is not symmetrical with the polepieces associated with the electromagnet. Hence when the electromagnet is energised, the additional flux becomes effective to move the armature to one side or the other and the subsequent flux reversals then maintain a regular swing. Alternatively the armature may be spring-biased to a non-symmetrical normal position.

I claim:

1. In a ringer having gongs, a non-magnetic element pivoted at one end and having striking

55 screws 16, 18, 17 and 19. The free ends of the

faces at opposite sides of the other end, a permanent magnet disposed between said faces, electromagnets having polepieces disposed on opposite sides of said permanent magnet, energization of said electromagnets causing movement of said element as a pendulum to cause said faces to alternately strike said gongs.

2. A ringer such as claimed in claim 1 in which said permanent magnet maintains said striking faces of the element spaced from said gongs when said electromagnets are not energized.

3. A ringer such as claimed in claim 1 in which said striking faces always follow each movement of said permanent magnet.

4. In a signalling device, a permanent magnet armature, a non-magnetic gong hammer being pivotally mounted at one end and provided with projections at the other end for serving as hammer heads, said armature being rigidly secured to said gong hammer at a position equidistant between said hammer heads, means for causing said armature to move said gong hammer in simple harmonic motion about said pivot.

5. In a signalling device, a pivoted gong hammer, a permanent magnet secured to one end of

25

said gong hammer and forming a movable armature, a first and a second electromagnet each having a plurality of polepieces, one polepiece of each electromagnet being adjacent to one end of said permanent magnet and the other polepiece of each electromagnet being adjacent to the other end of said permanent magnet, the windings of said electromagnets being so connected that when energized by alternating current the two polepieces adjacent to each end of said permanent magnet have dissimilar polarities.
